UNITED STATES PATENT OFFICE.

JOHN G. BAKER, OF AMSTERDAM, NEW YORK, ASSIGNOR OF ONE-HALF TO EARL BULLIS, OF AMSTERDAM, NEW YORK.

BUNCH BUILDER.

Application filed January 15, 1925. Serial No. 2,524.

To all whom it may concern:

Be it known that I, JOHN G. BAKER, a citizen of the United States of America, and a resident of Amsterdam, in the county 5 of Montgomery and State of New York, have invented a new and useful Bunch Builder, of which the following is a specification.

My invention relates to improvements in 10 builder arms for spinning frames, and consists essentially of a cam-operated bunch-builder attachment for a builder arm, which attachment comprises a carrier pivotally connected with the builder arm, and provided with a cam roll, adjustable means for 15 said carrier, and trip mechanism for said carrier, said trip mechanism including a cam on the builder-arm worm shaft, and a cam arranged to act on said roll, together 20 with such other parts and members as may be necessary or desirable in order to render the bunch builder complete and serviceable in every respect, all as hereinafter set forth.

The builder arm, with which my bunch 25 builder is connected and used, and the closely associated parts and members or mechanisms, by means of which the ring-rail is caused to rise and fall and to make a progressive ascent, are retained. As a 30 matter of fact the builder arm, builder cam, and let-off are so intimately associated and combined with the new elements that they may be said to constitute parts of the bunch builder itself. The bunch builder cuts 35 down or reduces the stroke or throw of the builder arm, during the initial or a first period of the operation of said arm. In consequence of this reduction of the oscillatory movement of the builder arm, both the 40 up and down movement and progressive ascent of the ring-rail are reduced or decreased in extent.

My invention is used in connection with 45 filling wind, where the yarn is wound on a bobbin or filling quill in short layers each being approximately one and one-half inches in length, beginning near the bottom of the quill and approaching the top, but without changing the length of the layer.

50 Yarn is wound on the bobbin in this manner for use in a shuttle in a loom, and so that the yarn can be pulled off of the end of the bobbin, or in a direction parallel with the axis of the same.

55 In the event the yarn on a filling bobbin

in a shuttle runs out and the loom thereafter makes one or more picks, a mark is left in the cloth, consequently it is necessary that the bobbin, before it becomes entirely empty, be removed from the shuttle 60 and replaced with a full bobbin, and this must be done with as little waste of yarn as possible. The primary object of my invention is, therefore, to provide in connection or combination with a builder arm mechanism for reducing to the minimum the aforesaid waste.

On a loom is a device known as a "battery" which automatically changes the bobbin in the shuttle between picks of the loom. 70 This device is caused to operate through the agency of a "feeler," which latter is adjusted to act when there is no longer sufficient yarn on the bobbin in the shuttle to support it. It is evident that this feeler must be set to act, however, while there is still some yarn left on the bobbin, in order to compensate for the variation in the sizes of bobbins, and, furthermore, since the taper of the yarn on the bobbin is ordinarily 75 long, said feeler must be set to act at a point some distance above the bottom of the bobbin. It follows, therefore, that a considerable amount of yarn must be left on the bobbin when the latter is knocked out 80 of the shuttle, if all liability of leaving "shuttle marks" is to be avoided. This yarn is stripped from the bobbin and becomes "thread waste" which is relatively 85 valueless. By building up the yarn quickly 90 to an appreciable thickness with a short stroke or layer, as I do with my bunch builder, a bunch of sufficient size to hold up the feeler is made with at least one-half 95 of the amount of yarn required heretofore. Furthermore, since the stroke with the builder arm is greatly reduced, the amount 100 of let-off of the builder-arm chain is correspondingly reduced, and this let-off controls the taper of the yarn on the bobbin, and produces a bunch which is very obtuse 105 at the bottom. In consequence of this the feeler can be set nearer the bottom of the bobbin, and there is much less yarn left on the bobbin when it is knocked from the shuttle.

Another advantage of the obtuseness or abrupt outward flare of the taper produced by my bunch builder is that the bunch with such taper is built up to a considerable size 110

before the ring-rail is permitted to make its regular stroke and let-off, with the result that space on the bobbin is completely, instead of only partially as ordinarily, filled.

- 5 Thus more yarn is wound on the same bobbin and the spinning-frame does not need to be stopped so often to "doff" or change bobbins; furthermore, the bobbins run longer in the loom, less bobbins are knocked out of 10 the loom in a given time, and there is less waste of yarn. Herein, then, is found another object of my invention.

Further objects are to provide a bunch builder which can be combined, requiring 15 but very little change, with a builder arm of the ordinary type, is comparatively inexpensive and simple both in construction and operation, and is automatic in both the tripping and resetting operations.

- 20 With this bunch builder the bunch is tightly wound on the bobbin, because the ring-rail is not permitted to stop during the winding operation, and consequently the yarn does not "rope off," as so frequently is 25 the case when other types of bunch builders are employed.

From the foregoing it is seen that this bunch builder effects a saving of approximately one-half of the bunch as ordinarily 30 formed on the bobbin, and that gain results from the increase in time between doffing, whereby the spinning-frame is in productive use during longer periods, and there is a saving in time of the operators.

- 35 Other objects and advantages will appear in the course of the following description.

I attain the objects and secure the advantages of my invention by the mechanism illustrated in the accompanying drawings, 40 in which—

Figure 1 is a front side elevation of the head-end portion of a spinning-frame, such portion extending high enough to include a ring-rail and roller beam on that side, 45 and having incorporated therewith a bunch builder which embodies a practical form of my invention; Fig. 2, a transverse vertical section through the aforesaid portion of the spinning-frame, taken on lines 2—2, looking 50 in the direction of the associated arrow, in Fig. 1; Fig. 3, an enlarged side elevation of a bobbin with a bunch built thereon with the aid of said bunch builder; Fig. 4, a side elevation of said bobbin when completely 55 wound or full; Fig. 5, an enlarged side elevation of a bobbin having the yarn wound thereon without the aid of said bunch builder; Fig. 6, a side elevation of said last-named bobbin showing the amount of waste 60 yarn left at the time the bobbin is knocked out of the shuttle; Fig. 7, an enlarged top plan of the builder arm and bunch builder, without the cams and with parts broken away; Fig. 8, an enlarged end elevation of 65 the bunch-builder carrier; Fig. 9, an en-

larged side elevation of the bunch builder, showing the same after being tripped, and, Fig. 10, an enlarged side elevation of the adjusting arm of the bunch builder.

Similar reference characters designate 70 similar parts throughout the several views.

In describing the old parts of the spinning-frame, the description will generally be confined to one ring-rail and one bobbin.

In the general views only so much of the 75 spinning-frame is illustrated as is necessary to an understanding of the construction and, operation of my bunch builder. Only one bobbin is shown in place in the first view, and the lower portions of a bobbin on each 80 side in Fig. 2. In practice, there are, of course, a large number of bobbins on each side of the spinning-frame.

I will first briefly describe the old parts 85 and members, including the builder arm, of the spinning-frame, illustrated in connection herewith.

The supporting parts of the spinning-frame which appear comprise a vertical head 1, a sampson or center leg 3, longitudinally-extending spindle rails 4, a cross girt 5, and a roller beam 6. There is a spindle rail 4 on each side of the spinning frame, and supported on each of these rails is a base 7 of a spindle (not shown) for a filling 90 quill or bobbin 8, and provided with a pulley 10 which is driven in the usual manner by means of a belt 11 from a cylinder 12. One end of the cylinder 12 is supported at 13 from the head 1. A ring-rail is represented 95 at 14 on each side of the spinning-frame. Each bobbin 8 extends through one of the ring-rails 14, and through a spinning-ring 15 on said ring-rail. The thread or yarn, represented at 16 in Fig. 1, passes downwardly, 100 from the drawing-rolls (not shown), of the spinning-frame, through suitable guides to the bobbin 8 in that view. Some of the parts and members thus far described are more or less fragmentary.

A bearing bracket 17 depends from the cross girt 5, and a shaft 18 is journaled in the head 1 and said bracket, and has mounted thereon and secured thereto a builder cam 19. A builder arm is represented at 20, and this is mounted on a rock-shaft 21 which is journaled in the head 1 and a bearing bracket 22 that also depends from the girt 5. The bracket 22 has an adjustable connection with the girt 5 longitudinally there- 110 of for the purpose of balancing the stroke of the builder arm, or evenning the amount of 115 time which it takes for said arm to make the up and down portions of the complete 120 stroke of the same.

The ring-rails 14 are arranged in sections 125 in the customary manner, and each of such sections is supported on lift rods 23, there being two of such rods or each section on each side of the machine, although but one 130

appears in the first view. Each rod 23 has its base pivotally connected with the free terminal of a lift lever 24, and said lever at the opposite end is mounted on and secured to a rock-shaft 25 which is journaled in a bracket 26 that depends from each of the spindle rails 4. An extension 27 from the lever 24 is provided with a weight 28 which is a counterbalance for the ring-rail 14. An arm 29 rises from the rock-shaft 25, is provided on top with a sector 30, and constitutes a part of the let-off or lifting mechanism for the ring-rail. A chain 31 has one terminal secured at 32 to the sector 30, and the other terminal connected at 33 with the builder arm 20, through the medium of a short length of chain 34 and other parts and members presently to be described. The chain 31, on its way from the chain 34 to the sector 30, passes over a sheave 35 carried by the spindle rail 4 and located above the builder arm 20. The axis of the sheave 35 is at right-angles to the longitudinal direction of the builder arm. The length of the stroke of the builder arm is regulated by adjusting the chain sector arm 29 on the rock-shaft 25.

Obviously, if the builder arm 20 be oscillated on or with the rock-shaft 21, such oscillatory movement must be imparted to the ring-rail 14, through the medium of the chains 34 and 31, the sector 30 and arm 29, the rock-shaft 25, the lever 24, and the rod 23, (there are actually two levers 24 and two rods 23 for each ring-rail). The adjustment of the length of the chain 31 at its point of connection (32) with the sector 30 controls the position from which the ring-rail 14 starts after doffing.

40. There is a rock-shaft lever or arm as 29 for each ring-rail section, and such levers or arms on each side of the spinning-frame are connected by tie-rods, a part of one of which is represented at 35.

45. Pivotally connected at the upper terminal, as indicated at 37, to a lug on the front spindle rail 4, is a let-off rod 38 on which are upper and under adjustable collars 39—39. The rod 38 is located near the head 1.

50. As will hereinafter be made plain, the upper collar 39 determines the amount of progressive movement upwardly imparted to the ring-rail 14 by the let-off mechanism, and the lower collar 39 serves as a stop to limit the builder arm when forced downwardly at the time the spinning-frame is doffed.

55. The builder arm 20 extends toward the head 1 from the shaft 21, and in the front side of said arm, adjacent to the left-hand or free end thereof, is a recess 40 into which a stud 41 projects. Loosely mounted on the stud 41 is a worm-wheel 42, said worm-wheel being in the recess 40. The worm-wheel 42 has rigidly connected therewith on

the front side, and also mounted on the stud 41, but outside of the recess 40, a pulley 43. The lower terminal of the chain 34 is secured to the periphery of the pulley 43, and said chain passes upwardly from the right-hand side of said pulley to be attached to the chain 31. A lug 44 extends into the recess 40 from the back side thereof to form a stop for a web or stop 45 on the back side of the worm-gear 42, so that the rotation of said worm-gear and the pulley 43 is limited. On the underside of the arm 20, adjacent to the free end thereof, is a bearing lug 46, and to the right of said lug is a lug 9. A shaft 47 is journaled in these two lugs, and projects beyond the left-hand end of the lug 46. A worm 48 is secured to the shaft 47 in position to intermesh with the worm-gear 43. Secured to the protruding front terminal of the shaft 47 is a ratchet-wheel 49, and mounted on the hub of said ratchet-wheel, between the ratchet-wheel and the adjacent end of the arm 20, is a counterweighted ratchet or let-off arm 50 which is provided at the inner or rear terminal with a pawl 51. The pawl 51 is pivoted at 52 to the arm 50, and with its lower end engages the ratchet-wheel 49. The direction of the ratchet-wheel teeth is such that the ratchet-wheel is actuated in the direction to cause the shaft 47 and worm 48, and the worm-wheel 42 and pulley 43, to let off or unwind the chain 34 from said pulley, when the builder arm swings upwardly, provided the let-off arm 50 be held at the inner end and thereby caused to rock on its axis with the upwardly-swinging builder arm. The let-off arm 50 is provided with the customary stops 91—91 to contact with the builder arm and prevent said let-off arm from assuming an inoperative position.

As shown in Fig. 7, there is a space 53 between the inner-end portion of the let-off arm 50 and the pawl 51, such space at the inner end being defined by a lug 54 at the extreme inner end of said arm. The rod 38 passes through the space 53, and the collars 39 are above and below the space-forming parts of the arm 50 and pawl 51.

By setting the upper collar 39 so that the pawl 51 encounters the same, during the upward movement of the builder arm 20 and before said arm arrives at the end of its up stroke, said pawl is caused to impart to the ratchet-wheel 49 a partial revolution, and thus to let off the chain 34, the amount of let-off depending on the setting of said ratchet-wheel and the number of picks such setting provides for, as the chain 34 is let off of the pulley 43, the lift or take-up mechanism is permitted to carry the ring-rail 14 higher, irrespective of the movement imparted to said ring-rail by the cam 19.

When the builder arm 20 swings downwardly again it carries with it the let-off

arm 50 and the pawl 51, which latter rides idly over the ratchet-wheel 49 and takes position in readiness to let-off again upon the next upward swing of said builder arm.

5 Secured to the back side of the builder arm 20 is a bracket 55 which forms two bearings 56 and 57 for a roll 58 that normally bears against the cam 19, being actuated toward the same by the weight 28 and the intervening parts and members. The cam 19 has three high and three low points, and is so shaped that it imparts to the arm 20, through the medium of the roll 58, a slow downward movement and a quick upward movement, and causes said arm to be oscillated three times at each revolution of said cam. As the cam 19 is rotated and the arm 20 oscillated thereby, the ring-rail 14 is raised and lowered accordingly and the yarn 16 is wound on the bobbin 18 in the usual manner. Meanwhile or each time the roll 58 enters one of the depressions in the cam 19 and the arm 20 swings upwardly, the let-off mechanism operates and in turn causes the lifting mechanism to operate and elevate the ring-rails 14, again in the usual manner.

The setting of the let-off mechanism is accomplished by rotating the shaft 47 in the reverse direction until the stop 45 on the worm-wheel 42 encounters the stop 44 on the backside of the recess 40 in the arm 20. At this time the chain 34 is wound on the pulley 43, which is a part of or incidental to the doffing operation. While the stop 45 is in contact with the stop 44, the let-off arm 50 is rocked on the hub of the ratchet-wheel 49 to position the pawl 51 in proper relation to said ratchet-wheel, so that, when said arm and pawl encounter the upper collar 39, said pawl is held by said collar in active engagement with the ratchet-wheel teeth and the continued upward movement of the builder arm causes the ratchet-wheel to be partially rotated. By this means and in this manner is imparted the movement necessary to lift the ring-rail 14 the required distance, because the pawl 51 actuates the ratchet-wheel 49 the number of teeth which corresponds with the distance that said ring-rail is to be elevated each time the let-off operates.

In Fig. 5 is represented a full bobbin as it would appear if wound in its entirety through the medium of the cam 19. It will be observed that the yarn on this bobbin has a long straight taper at the bottom. In Fig. 6 is shown the same bobbin from which the yarn has been unwound, leaving a bunch 59, which bunch is quite long and represents a large amount of waste. In each of these views and in each of Figs. 3 and 4 a feeler is represented at 60. By greatly reducing the stroke of the builder arm 20, the amount of let-off of the chain 34, which let-off con-

trols the taper of the yarn on the bobbin, is reduced accordingly, which results in winding more yarn on the bobbin at the bottom, in producing a bunch with a very obtuse taper, and in rounding out the yarn at the bottom. Such being the case, the feeler 60 can be set near the bottom of the bobbin, much nearer than formerly, and there will be much less yarn on the bobbin when it is knocked from the shuttle. Such a bunch is represented at 61 in Fig. 3, and the fully wound bobbin in Fig. 4. The difference in the amount of yarn on the bobbins illustrated in Figs. 4 and 5, where the feeler 60 contacts with the same in each case, clearly shows how much more yarn is wound on the first of these two bobbins.

To obtain with the mechanism hereinbefore described the results just pointed out, I make use of a bunching cam 62, which is mounted on and secured to the same shaft 18 with the builder cam 19, a cam 63 mounted on and secured to the worm-shaft 47, a carrier 64 for a roll 65, a latch 66, an adjusting arm 67, a spring 68, and a resetting chain 69.

The cam 62 has three high points and six indentations with three arcs between said indentations, substantially as best shown in Fig. 9, and said cam is so arranged relative to the cam 19 that the high points of the former prevent the roll 58 from entering the depressions in the latter, and thereby materially limit the upward movement of the builder arm 20 during the effective operation of the bunch cam. By thus cutting down the movement of the arm 20, the movement imparted to the ring-rail 14 by the lifting mechanism is correspondingly decreased.

A plate 70 is secured to the front side of the builder arm 20, and a bolt 71 extends forwardly through the bracket 55, said arm, and said plate, to receive on the front terminal a washer 72 and a nut 73, with a sleeve 74 interposed between said plate and said washer. The carrier 64 is loosely mounted on the sleeve 74, and said carrier has a rear arm 75 and a front arm 76 which form bearings 77 for the trunnions of the roll 65. In the lower part of the arm 75 is an arcuate slot 78 to receive a bolt 79, with a washer 80 interposed between said arm and the head of said bolt. The adjusting arm 67 is an arcuate member which has a lip 81 at the top for the attachment thereto of the lower end of the chain 69, a hook 82 on the outer edge adjacent to the top thereof, and a forwardly-extending lug 83 at the bottom to receive an adjusting screw or bolt 84. There is an opening 85 tapped into the arm 67 to receive the bolt 79. The spring 68 has one terminal attached at 86 to the outer edge of the arm 67. The latch 66 is pivoted at 87 to the front side and adjacent to the left-

hand end of the plate 70, and is adapted to have its upper end thrust beneath the hook 82 on the arm 67, being actuated into such position by the spring 68 when the latter is brought into contact with the right-hand edge of said latch below the horizontal plane of the pivot 87. This occurs when the carrier 64 is swung upwardly by the chain 69. The left-hand edge of the latch 66, below the horizontal plane of the pivot 87, has a projection 91 which is thrust into the path of the cam 63, when said latch is acted on by the spring 68. The upper end of the chain 69 is attached at 88 to the roller beam 6.

15 Normally there is a sufficient amount of slack in the chain 69, to prevent said chain from interfering with the action of the builder arm and parts carried thereby.

In doffing, the builder arm 20 is forced 20 downwardly as far as the lower collar 39 will permit, and such operation takes the slack out of the chain 69 and the latter swings the carrier 64 upwardly, from the position which it occupies in Fig. 9 to the 25 position which it occupies in the other views where the same appears. The carrier 64 in its upward movement at this time carries the spring 68 into contact with the latch 66, and said spring rocks said latch on the pivot 87 30 in the direction to thrust the upper end of said latch beneath the hook 82 and the projection 92 into the path of the cam 63. When the arm 20 is swung upwardly again 35 into operative position, the roll 65 comes into contact with the cam 62, and the hook 82 supports the carrier 64 on the latch 66. This last is made possible because the chain 69 causes the carrier 64 to be swung upwardly far enough to admit the latch 66 40 beneath the hook 82, and then, when said chain is slackened at the time the builder arm is swung upwardly from doffing position, the chain permits said carrier to swing down into supporting relation with said 45 latch.

The builder arm 20 now receives impulses from the bunching cam 62, as well as from the builder cam 19, and is never permitted by said bunching cam to enter the depressions in said builder cam. The cam 62 cuts down the oscillatory movement or the upward stroke of the arm 20, and correspondingly decreases the rise of the ring-rail 14. It should be noted in passing that, with the 50 cams 19 and 62 constructed and relatively proportioned as shown, the roll 65 is on a higher plane than the roll 58. The decrease in the normal rise of the ring-rail causes the bunch 61 to be spun on the spindle and the yarn to be filled in at the bottom so that the quantity of yarn spun on the spindle is increased, as hereinbefore explained. The bunch 61 is only about one-half as long and contains only about one-half as much waste 55 as the bunch 59.

The bunching cam 62 continues to operate and the arm 20 to have the short upward strokes imparted thereto until the trip cam 63 makes one revolution, when said trip cam actuates the latch 66 out of engagement with the hook 82, and permits the carrier 64 to swing downwardly and carry the roll 65 away from said bunching cam, after which, or until said carrier is reset, the bunching cam continues to operate idly.

70 The chain 69 must be the proper length to leave the amount of slack therein necessary to prevent it from interfering with the operation of the bunch builder, and to bring about the resetting of the latter when the arm 20 is forced downwardly for doffing purposes.

75 The height of the roll 65, when said roll is in operative position, is regulated by means of the adjustment afforded by the arm 67. Upon loosening the bolt 79, and if necessary the bolt 84, the arm 67 may be adjusted longitudinally, with the bolt 79 in the slot 78, to whatever extent may be necessary, and then said bolt 79 is retightened 80 and said bolt 84 is screwed against the adjacent edge of the arm 75. The bolt 84 directly supports the carrier from the arm 67, assisted by the bolt 79 and the friction between the parts held together by said last-named bolt when tightened. If the roll 65 be set higher, the upward movement permitted by the cam 62 to the arm 20 is decreased, and, if said roll be set lower, such 85 movement is increased.

90 With each revolution of the shaft 18, during the bunch-building operation, the builder arm 20 is oscillated three times by means of the cam 19 and three times by means of the cam 62, or six times in all, the 95 amount of oscillation imparted by each cam being approximately the same. As the arm 20 rises each time, the let-off is operated to unwind the chain 34 and permit the ring-rail 14 to ascend so as to rise and fall the 100 next time between two higher levels, but very much less of said chain is unwound than is the case when the builder arm is operated solely by the builder cam. Consequently, by the time the cam 63 trips the 105 latch 60 to release the carrier 64, the bunch 61 is wound and the bottom of the winding on the bobbin is filled in and built out to the required extent.

110 The period of action of the let-off mechanism is greater than one-half of the time which it takes for the builder arm to make its upstroke. Thus it appears that in reducing the stroke of the builder arm with my bunch builder the amount of let-off is 115 greatly reduced, but the bunching cam must be so constructed that each up stroke thereby permitted to the builder arm is sufficient to produce a let-off of at least one tooth. In other words, the bunching cam must permit 120 125 130

the builder arm to make a stroke of sufficient length to enable the let-off to make at least one pick.

As soon as the carrier 64 is released and 5 swings down into its inactive position, the builder cam 19 commences to actuate the builder arm in the natural way, and with and through said arm the let-off and the lifting mechanism, the latter then elevating 10 the ring-rail 14 the full distance permitted by said let-off as and each time that the roll 58 enters one of the depressions in said cam.

As the end of the spinning operation, the machine is doffed, during which time the 15 bunch builder is reset and the chain 34 is rewound on the pulley 43, the latter operation being performed by rotating the worm-shaft in a reverse direction by means of a suitable tool applied thereto.

20 The chain 34 can not unwind or be unwound except by means of the let-off, due to the fact that the worm 48 is a single-lead worm and of the type known as self-locking, and to the friction between the parts. In 25 order to increase the aforesaid friction a spiral-spring 89 is arranged on the shaft 47 between the hub of the ratchet-wheel 49 and the inner end of an enlargement of the bore in the bearing lug 46, as shown in Fig. 7. 30 The low pressure angle of the worm and worm-gear and the friction between the parts prevent said worm-gear from moving said worm, but do not prevent the latter from readily moving the former.

35 More or less change in the shape, size, construction, and arrangement of some or all of the parts of this bunch builder may be made without departing from the spirit of my invention or exceeding the scope of what 40 is claimed.

What I claim as my invention, and desire to secure by Letters Patent, is—

1. In a bunch builder, a builder arm of a spinning-frame, said arm being provided 45 with let-off mechanism which consists in part of a shaft, cam-operated means carried by said arm to reduce the movement thereof during a first period of its operation, and a trip device also carried by said arm for said 50 means, and a cam on said shaft to operate said trip device.

2. In a bunch builder, a builder arm of a spinning-frame, said arm being provided with let-off mechanism which consists in 55 part of a shaft, cam-operated means carried by said arm to reduce the movement thereof during a first period of its operation, and a trip device also carried by said arm for said means, a cam on said shaft to operate said trip device, and means automatically to reset said carrier when said arm is actuated downwardly for doffing purposes.

3. In a bunch builder, a cam-operated builder arm of a spinning-frame, let-off 60 mechanism carried by said arm and pro-

vided with a rotary member, a carrier pivotally connected with said arm, a roll supported by said carrier, a cam, and oscillatory means carried by said arm and in the path of said rotary member normally to retain said carrier with said roll against said cam, the construction and arrangement of parts being such that said carrier is automatically released and permitted to remove the roll from contact with said cam, at the 75 end of a predetermined number of oscillations of said arm.

4. In a bunch builder, a cam-operated builder arm of a spinning-frame, let-off mechanism carried by said arm and consisting in part of a shaft, a cam on said shaft, a carrier pivotally connected with said arm and provided with a roll, a second cam, and a latch pivotally connected with said arm and adapted to retain said carrier with its 80 roll against said second cam, said latch being in the path of said first cam.

5. In a bunch builder, a cam-operated builder arm of a spinning-frame, let-off mechanism carried by said arm and consisting in part of a shaft, a cam on said shaft, a carrier pivotally connected with said arm and provided with a roll, an arm adjustably connected with said carrier, and a latch adapted to engage said second-named arm 95 and retain said carrier with its roll against said second cam, and to be operated by said first cam.

6. In a bunch builder, a cam-operated builder arm of a spinning-frame, let-off mechanism carried by said arm and consisting in part of a shaft, a cam on said shaft, a carrier pivotally connected with said arm and provided with a roll, an arm adjustably connected with said carrier and having a 100 projection, a latch adapted to engage said projection and retain said carrier with its roll against said second cam, and to be operated by said first cam to disengage said projection and permit said carrier to swing 105 downwardly and remove its roll from said second cam.

7. In a bunch builder, a cam-operated builder arm of a spinning-frame, let-off mechanism carried by said arm, a carrier pivotally connected with said arm and provided with a roll, a second cam, means to retain said carrier with its roll in contact with said second cam, means to trip said first-named means from said let-off mechanism, and a chain having one end attached to a fixed point and the other end connected with said carrier, whereby the latter is automatically reset when said arm is swung 115 downwardly during the doffing operation.

8. In a bunch builder, a cam-operated builder arm of a spinning-frame, let-off mechanism carried by said arm, a carrier pivotally connected with said arm and provided with a roll, an arm adjustably secured 120

to said carrier, a cam, means to retain said carrier with its roll against said cam, means to operate said first-named means from said let-off mechanism to permit said carrier to remove its roll from operative position relative to said cam, and a chain having one end attached to a fixed point and the other end attached to a second-named arm, and adapted to reset said carrier when said builder arm is swung downwardly during the doffing operation.

9. In a bunch builder, a cam-operated builder arm of a spinning-frame, let-off mechanism carried by said arm and consisting in part of a shaft, a cam on said shaft, a second cam, a carrier pivotally connected with said arm and provided with a roll, an arm adjustably affixed to said carrier and having a projection, a latch pivotally connected with said builder arm and adapted to engage said projection and retain said second-named arm with said carrier in position to retain said roll in contact with said second cam, said latch having a part to extend into

the path of said first cam, and a chain having one end attached to a fixed point and the other end attached to said second-named arm, and adapted automatically to swing upwardly and reset said carrier when said builder arm is swung downwardly for doffing purposes.

10. The combination, in a device of the class described, with a ring-rail, lifting mechanism for said ring-rail, a cam-operated builder arm provided with let-off mechanism, and connections between said lifting mechanism and said let-off mechanism, of cam-operated means carried by said arm to reduce the movement of said arm during a first period of its operation, means operated by said let-off mechanism to trip said first-named means, and means inactively connected with said first-named means until said builder arm is forced downwardly for doffing purposes, when said last-named means causes said first-named means to be reset.

JOHN G. BAKER.
